DOOR CHECK

Harold Vern Miller, Arlington, Va.

Application December 20, 1949, Serial No. 134,028

2 Claims. (Cl. 292—262)

1

The present invention relates to a door check for holding the door in partly closed locked position. More particularly the present invention relates to a door stop which, in combination with the conventional night chain, will hold the door in predetermined partly open position to provide ventilation while at the same time preventing unauthorized entry through the door.

The present invention is particularly adaptable to hotel rooms, apartments, and public dwelling and living quarters where there is a need for cross ventilation and security. While door checks of various types have previously been proposed for the purpose of keeping doors ajar, these devices do not provide satisfactory means for preventing entrance while the door is in an open position for ventilating the room.

It, accordingly, is a primary object of this invention to provide a suitable inexpensive door check to secure a door in partially open position.

A further object of the present invention resides in the provision of a novel door stop for use in combination with a conventional securing chain to provide ventilation and at the same time secure the door against unauthorized entry.

Still another object of the present invention resides in providing an expansible door stop co-operating with a night chain to maintain the door open to the extent permitted by the night chain.

Another object of the present invention resides in provision of a door stop which may be readily disposed either in operative or inoperative position.

Still another object of the present invention resides in mounting an expansible door stop on the door frame in predetermined relation to the conventional night chain so as to cooperate in one position with the night chain to lock the door in open position and in its other position to be disposed out of the entrance way to provide free passage through and past the door.

Other objects will become apparent as the description proceeds in connection with the appended claims and accompanying drawings wherein:

Figure 1 is a front elevation of a preferred embodiment of the present invention.

Figure 2 is a top plan view of Figure 1.

Figure 3 is a transverse sectional view, and

Figure 4 is a perspective view of a modified form of the present invention.

Referring to the drawings wherein like reference numerals indicate the same parts throughout, the door check of the present invention is

generally indicated by the reference numeral 10 and comprises a door securing element such as the conventional night chain, generally indicated at 11 and a cooperating expansible door stop designated by numeral 12. A plate 14 preferably secured to the door jamb 16 by means of screws 18 supports the securing element 11 and stop 12. To this end, plate 14 carries a staple 20 and is provided with a ball socket portion 22 the purpose of which will be described later.

The door 23 preferably is provided with a latch plate 24 fastened to the door by means of screws 28. Plate 24 has an elongated undercut slot 30 formed therein to receive a slidable T shaped securing plate 32 to which one end of a chain 36 is attached by means of a staple 37 or other suitable means in conventional manner. The opposite end of chain 36 is suitably connected to staple 20 in well known manner.

The door is secured against full opening movement by inserting the T portion of plate 32 into the enlarged opening 29 in slot 30 and sliding the plate along slot 30 in well known manner. The night chain, as is well known, allows the door to be opened a predetermined distance for the purpose of viewing whoever might wish entrance. It will be appreciated that maintenance of the door in this partly open position will afford desirable ventilation. This invention contemplates accomplishment of this end by provision of the expansible door stop 11 operating in co-operation with the night chain.

The door stop 12 may assume any suitable form but preferably comprises an axially compressible rod-like member. Such member may take the form of a hollow casing 38 having an annular end flange 40 which increases the rigidity of the casing at one end and also provides an abutment the purpose of which will presently appear. The casing 38 at its opposite end has a reduced portion 42 into which a rod 44 carrying a bumper member 46 is rigidly fixed.

Within the casing 38 is a compression spring 48 which is confined between an offset portion 50, formed in casing 38, and an enlarged end member 52 fixed to a rod 54 the other end of which is loosely held in socket 22 of plate 14. The enlarged end 52 of rod 54 is mounted for sliding movement in casing 38 and confined against removal from the end of casing 38 by a cap 56 press fitted into the end of casing 38. The cap 56 has an annular outwardly directed flange 58 and an inwardly directed flange 60 connected by an intermediate portion 61 substantially parallel to the axis of rod 54. The depending

flange 60 of cap member 58 acts as an abutment to limit the stroke of the rod 54. The other end (3) of rod 54 is movably secured to plate 14 in any suitable manner but preferably comprises a ball connection 62 cooperating with ball socket 22 to provide a limited universal mounting of the door stop on plate 14. The ball socket 22 preferably has an elongated slot 64 disposed vertically with respect to the door frame and adapted to freely receive the rod 54 to permit the door stop to assume a position parallel to the door jamb 16 when in an inoperative position. As a consequence, the door stop is normally out of the way but conveniently accessible for use when desired.

Figure 4 discloses a modified form of the door stop of the present invention adapted for use in conjunction with night chains already installed to provide a door check having the advantages of the present invention. In this form, a plate 66 having a ball socket portion 22 and adapted to be separately mounted on a door frame in juxtaposition to the night chain mounting plate is provided. Since the only difference between this form of the invention and that previously described is the separable mounting plates, the same reference numerals have been employed in the drawings and a further description of the parts is omitted. Also since the operation of the door check of this invention is believed to be clear from the preceding description and drawings a detailed description of operation is believed unnecessary and will be omitted.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. A door check cooperating with a door member and a frame member to secure said door member in partly open position comprising a mounting plate adapted to be secured to one of said members; a latch plate adapted to be secured to the other of said members; a night chain

of predetermined length connected at one end to said mounting plate and having a securing plate secured to its other end adapted to cooperate with said latch plate to removably secure said other end of said chain to said other member and thereby adapt said chain to limit the opening movement of said door member to an extent whereby disassociation of said latch plate and said securing plate is rendered impossible within the limited opening movement permitted; and a resilient axially expansible door stop having an axial dimension when fully expanded in excess of the limited opening permitted by said chain, one end swingably mounted on one of said members and its other end adapted to abut the other of said members and force the door open to the limited extent permitted by said chain whereby said chain and door stop cooperate to yieldingly secure said door member open to the limit of the opening movement permitted by said chain.

2. A door stop adapted for cooperation with a night chain to provide a door check for securing a door in partly open position comprising a rod-like member having one end adapted to be swingably mounted on a mounting plate; a tube-like member telescopically receiving the other end of said rod-like member and having an abutment element at the end remote from said rod-like member; a compression spring disposed within said tube-like member and operable to yielding urge said rod-like member and said tube-like member in opposite directions; and a cap press fitted in the other end of said tube-like member to provide a stop for preventing disassociation of said members and having an axial opening therethrough for freely receiving the intermediate portion of said rod-like member.

H. VERN MILLER.
